UNITED STATES PATENT OFFICE.

OTTO DE LORENZI, OF MAPLEWOOD, NEW JERSEY, ASSIGNOR TO INTERNATIONAL COMBUSTION ENGINEERING CORPORATION, OF NEW YORK, N. Y., A CORPORATION OF DELAWARE.

FURNACE.

Application filed September 4, 1925. Serial No. 54,404.

My invention relates to furnaces and has which is particularly adapted for use in 55 special reference to traveling grate furnaces cases where the gas passes of the boiler are of the type which are particularly adapted of greater width than the combustion chamber of the furnace.

Another object of the invention is to provide a novel and improved combustion 60 chamber for a boiler furnace.

The several features of the invention, whereby the above mentioned and other objects may be attained, will be clearly understood from the following description and 65 accompanying drawings, in which:

Figure 1 is a longitudinal sectional view of a traveling grate boiler furnace embodying the features of the invention in their preferred form, the section being taken substantially on the line 1—1 of Fig. 2; and 70

Fig. 2 is a detail sectional plan view, partly diagrammatical, taken on the line 2—2 of Fig. 1.

The traveling grate furnace illustrated in 75 the drawings, which is particularly adapted for use in burning coke breeze and other low grade fuels, is provided with the usual chain grate 2, and combustion chamber having longitudinally extending side walls 4, front and rear walls 6 and 8, a front arch 10 and a rear arch 12. The rear arch extends over approximately one-half the length of the fuel supporting portion of 80 the grate and is spaced from the front arch 10 so as to provide a relatively narrow gas pass 14 extending between the side walls and leading to the tubes 16 of the boiler, the walls of the gas pass diverging upwardly 85 to the boiler tubes. 90

In traveling grate furnaces of this type as heretofore constructed, the gas pass extending between the side walls has usually been of uniform width throughout its length, with the result that there is a tendency of the gases in following the path of 95 least resistance to concentrate at the center of the gas pass, and thus the greater portion thereof flow through the central portion of said gas pass and the gas passes of the boiler, which of course is objectionable. Such central flow of the combustion gases is particularly noticeable in cases where the boiler is of greater width than the combustion chamber of the furnace, as in such cases very 100 little, if any, of the gases reach the side portions of the gas passes of the boiler. 105

An object of the present invention is to provide a traveling grate furnace of the character indicated in which there is provision of means for insuring a more even distribution of the combustion gases throughout the width of the gas passes of the boiler, thus securing a more efficient utilization of the heat of the gases.

Another object of the invention is to provide a novel and improved combustion arch construction for a traveling grate stoker

To overcome such objectionable features

of the prior constructions, in my approved furnace as illustrated in the drawings, the gas pass 14 between the front and rear arches of the combustion chamber diverges 5 in width from substantially its center toward its ends so that less restricted paths are provided for the flue gases adjacent the side walls of the furnace than near its center, and it will be apparent by making such 10 variation in the width of the gas pass of the proper proportion, that a substantially uniform distribution of the waste gases throughout the length of the gas pass may be secured. This construction is particularly 15 advantageous in cases where the boiler is of greater width than the combustion chamber of the furnace as it insures a material portion of the waste gases reaching the extreme side portions of the gas passes of 20 the boiler. In the illustrated construction I have provided such variation in the width of the gas pass by providing the opposed walls of the front and rear arches with opposed stepped portions 18 substantially at 25 the center thereof, opposed stepped portion 20 adjacent the side walls of the combustion chamber, and opposed stepped portions 22 between the portions 18 and 20. I have found that satisfactory results may be secured 30 in a furnace where heretofore the lower portion of the flue gas pass 14 has been of a width of substantially three feet throughout its length, by spacing the stepped portions 18 two feet six inches 35 apart, the intermediate stepped portions 22 three feet apart, and the end stepped portions 20 three feet six inches apart, although it will be apparent that the proportions may be varied to meet different conditions.

It will be apparent that my improved construction not only insures a more uniform distribution of the gases throughout the gas passes of the boiler, but also insures 45 a more thorough and uniform mixing of the gases within the combustion chamber.

As will be evident to those skilled in the art, my invention permits various modifications without departing from the spirit 50 thereof or the scope of the appended claims.

What I claim is:

1. A boiler furnace having a combustion

chamber having longitudinally extending side walls, and a roof having a relatively narrow gas pass extending transversely 55 thereof and leading to the boiler, and increasing in width from substantially its center toward said side walls.

2. A boiler furnace having a combustion chamber having longitudinally extending 60 side walls, and a roof having a relatively narrow gas pass extending transversely thereof, leading to the boiler, and being of greater width near its ends than near its center. 65

3. A furnace having, in combination, a traveling grate, a combustion chamber having longitudinally extending side walls arranged adjacent the longitudinal sides of said grate, front and rear arches extending 70 over said grate and spaced apart with their opposed wall portions diverging from substantially their center toward said side walls to provide a gas pass increasing in width from substantially its center toward its ends. 75

4. A furnace having, in combination, a traveling grate, a combustion chamber having longitudinally extending side walls arranged adjacent the longitudinal sides of said grate, and front and rear arches extending 80 over said grate and spaced apart with their opposed wall portions of stepped formation to provide a gas pass increasing in width from near its center toward its ends. 85

5. A boiler furnace having, in combination, a traveling grate, a combustion chamber having longitudinally extending side walls arranged adjacent the longitudinal sides of said grate, a front arch, and a rear 90 arch extending over substantially one-half of the length of the fuel supporting portion of said grate and spaced from said front arch so as to provide a narrow gas pass extending between said side walls and leading 95 to the boiler, the walls of said gas pass diverging upwardly toward the boiler and the lower portion of the walls of said gas pass diverging from substantially their center toward said side walls. 100

In testimony whereof, I have signed my name to this specification this 2nd day of September, 1925.

OTTO DE LORENZI.
